CLAIM

The ornamental design for a game dart shaft or similar
article, substantially as shown.

DESCRIPTION

FIG. 1 is a front elevational view of a game dart shaft or
similar article according to our design.

FIG. 2 is a perspective view of the game dart shaft as
shown in FIG. 1.

FIG. 3 is a front side elevational view of the shaft.

FIG. 4 is a back side elevational view of the shaft.
